UNITED STATES PATENT OFFICE.

EDWARD E. CLAUSSEN, OF HARTFORD, CONNECTICUT.

PAPER-BAG MACHINE.

SPECIFICATION forming part of Letters Patent No. 634,081, dated October 3, 1899.

Application filed April 27, 1899. Serial No. 714,697. (No model.)

To all whom it may concern.

Be it known that I, EDWARD E. CLAUSSEN, a citizen of the United States, residing at Hartford, in the county of Hartford and State of Connecticut, have invented certain new and useful Improvements in Paper-Bag Machines, of which the following is a full, clear, and exact specification.

This invention relates to improved machinery for automatically manufacturing square-bottom paper bags from tucked-paper tubing, and as herein shown is being adapted to form the completed bottom, having the inwardly-projecting triangular folds and the pasted bottom seam folded transversely to that bottom, or the same is applicable to and adapted for a converter to transform such bags made in accordance with Letters Patent granted to L. C. Crowell February 20, 1872, bearing the No. 123,811 and known commercially as the "square" bag, the same being a bag having longitudinal folds and the bottom fold pasted transversely across the bag, and convert the same into the square-bottom paper bag of well-known form, the same being a bag having longitudinal folds and the characteristic inwardly-projecting triangular folds and the flaps of the diamond fold pasted longitudinally; but I will, however, describe in this application the machine adapted to make the square-bottom bag from a tucked tube.

Prior to this invention square-bottom paper bags have been manufactured by a series of manipulations, and the mechanisms and devices for making the steps of the successive formations have been very intricate and expensive, and it is therefore the object of this invention to provide a machine that is simple and reliable and to complete the bag-bottom by devices and mechanisms in a single operation. These devices may be used equally well as a converter for converting the square bag into the square-bottom paper bag and could be attached to any of the old-style machines by omitting certain parts of the machine, as the tube-severing devices and paste-applying mechanism, as will be more fully explained hereinafter.

In the preferred embodiment of this invention herein shown and described the paper-bag machine comprises in part a suitable bed

or framework, drawing-roll mechanisms for drawing the tucked-paper tube into the machine, a rotating striker revolving across the path of the tube, delivery-roll mechanism, bottom-forming mechanism embodying the stationary retainer and having means for effectively holding the upper ply of the tube thereto, a vibratory tucker-plate mounted in suitable stationary bearings, vibratory carriers mounted in suitable bearings in the framework and also provided with means for effectively holding the lower ply of the tube thereto, and a lifting-plate controlled by the movement of the carrier, all substantially as hereinafter described, and more particularly set forth in the claims. The mechanisms just described are adapted to hold the four sides in forming the bottom of the bag at any stage during the folding operation in a parallelogram and three sides of the mechanism forming substantially planes of that parallelogram.

In the drawings accompanying and forming a part of this specification, Figure 1 represents a sectional plan view on line 1 1 of Fig. 2 of the improved paper-bag machine. Fig. 2 is a sectional side elevation taken on line 2 2 of Fig. 1, showing a tucked-paper tube in the bite of the drawing-rolls and drawn into the machine, severed by the striker, and showing a paper-bag blank gripped by the bottom-forming mechanism ready for the folding operation to begin thereon. Fig. 3 is a fractional outside view of the cams and connections for operating the vibratory tucker-plate and the intermittently-rotating carrier. Fig. 4 is a sectional rear end elevation on line 4 4 of Fig. 2 as viewed in the direction of the arrows. Figs. 5, 6, and 7 are fragmentary plan, end, and side views of the bottom-forming mechanisms, respectively, the same being drawn on an enlarged scale to more clearly indicate the various detail constructions. Figs. 8, 9, 10 and 11 are edge views at different successive formations of the bag-blank when the bottom-folding mechanisms are in operation thereon.

The reference letters and numerals herein used indicate, respectively, the same parts in the different figures of the drawings. The arrows indicate, without further description, the direction of movement of parts.

In the accompanying drawings the positions of the various instrumentalities are shown to best advantage irrespective of the relative position these parts may have to their respective cam-grooves, and the same is true of all parts hereinafter mentioned, it being considered sufficient for the purpose of this description to assume that the cams are properly cut to effect the various operations required to at the proper times and to the required extent.

A description will first be given of the arrangement, construction, and mode of operation of each section of the machine and afterward their combined mode of operation will be described. For more clearness the gears 26, 27, 28, 29, 30, 31, and 125 are broken away; but it is understood that the teeth are cut around their full circumferences.

20 In the various views the numeral 20 indicates in a general way the bed of the machine, consisting mainly of the side frames 21 and 22, in which the various shafts, mechanisms, and devices are suitably mounted and supported, as will be more fully explained hereinafter.

Power is communicated to the machine by the pulley 23 in the direction of the arrow 24, securely held on the shaft 25, which is journaled in the side frames 21 and 22, and that shaft carries on the inner side of the frame 21 the gear 26, meshing into the gear 27, which meshes again into the gears 28 and 29, engaging the gear 30, thereby forming a complete train of gears 28, 29, 30, and 31, the gears 27 and 28 being fastened, respectively, on the shafts 32 and 33, the gear 29 revolving loosely on the stud 34, and the gears 30 and 31 being respectively rigidly secured to the shafts 35 and 36. Rigidly secured to the shafts 32 and 33 are the delivery-rolls 37 and 38 and to the shafts 35 and 36 the drawing-rolls 39 and 40, respectively.

45 Mounted on the shaft 36 and adjacent to the drawing-roll 40 is a miter 41, meshing into the miter 42 and fastened on the striker-shaft 43, journaled in projecting hubs 22^a and 22^b of the frame 22, and that shaft carries, also fastened thereto, the striker-arm 44, which 50 revolves across the path of the tube, carrying it against the serrated knife 45 and float 46, mounted, respectively, above the tube and inside thereof and severing the blank from the tucked-paper tube at each rotation thereof. 55 By the construction, organization, and arrangement of connections one tube length is severed and delivered into the bottom-folding mechanism, and the subsequent operations for completing the bag will now be described.

60 As a convenient means for supporting the stationary retainer 50 the frames 21 and 22 have inwardly-projecting lugs 21^c, 21^d, 22^c, and 22^d, respectively, upon which the retainer 65 is rigidly held, consisting substantially of a plate extending across the machine from the frame 21 to the frame 22, having the folding

edge 50^a, against which the portion of the bag-blank is pressed which is to form the pasted transverse cross-fold of the completed bag. 70 The distance from the folding edge 50^a to the center of oscillation of the tucker-plate 64 is substantially equal to the depth of the tuck of the paper tube, the purpose of which will be more fully explained hereinafter. 75 As a convenient means for holding the upper ply of the tube to the retainer bevel-edged side nippers 51 and 52 are provided, journaled for oscillation in lugs X and Y of the retainer and T and U of the side frames 21 and 22, respectively, in substantially such a position that the line passing through the intersecting points of the bevel-edged side nippers and the edges of the tube form eventually the edge R of the completed bag-bottom. The side nippers 51 and 52 are rigidly held on shafts 53 and 54, provided at the end near the delivery-rolls with cam-arms 55 and 56, having projections engaging cam-grooves 57 and 58 of the cams 59 and 60 and whereby the vibratory motion is imparted to those nippers at each rotation of the shaft 33 at such intervals as to clip and hold the bag-blank as the same enters the bottom-forming mechanism and release its grip thereon when the bag-bottom 95 is completed.

90 In the lugs 21^c and 22^c of the frames 21 and 22 are journaled the trunnions 62 and 63, which support the vibratory tucker-plate 64 in substantially such a position that the center of oscillation of that vibratory tucker-plate coincides with the edge R of the completed bag-bottom, or, as previously stated, corresponds with the line passing through the intersecting points of the bevel-edged side nippers and the edges of the tube. The tucker-plate is provided with the folding edge 64^a, the distance from the center of vibration of that tucker-plate to its folding edge being substantially equal to the depth of the tuck 110 of the paper tube, and therefore the folding edge 64^a practically corresponds with the retainer edge 50^a of the retainer 50 when the tucker-plate is brought into the position as shown in Fig. 11. The trunnion 63 has fastened on the right-hand side adjacent to the frame 21 the pinion 65, meshing into the sector 66, which is pivotally mounted on the stud 67 and carries the roller projection 68, engaging the cam-groove 69 of the cam 70, fastened on the shaft 25, and whereby a vibratory motion is imparted to the tucker-plate 64 of about one hundred and eighty degrees.

115 The bottom-forming mechanism, which operates below the normal feed of the paper-bag blank, consists of the carriers 74 and 75, journaled upon shafts 76 and 77, the outer free ends of which have fastened thereto the pinions 78 and 79, meshing into the sectors 80 and 81, which are fastened to the shaft 82. The sector 81 has fastened thereto the cam-arm 83, having the roller projection 84 engaging the cam-groove 85, cut on the outer 120 125 130

side of the cam 70, and whereby an oscillatory motion is imparted to the carriers 74 and 75, respectively. The location of the shafts of the carriers in relation to the retainer and the oscillating tucker-plate is substantially such that the center of oscillation of those carriers coincides with the folding edge 50^a of the retainer, and the distance from the center of oscillation of the tucker-plate to the center of oscillation of the carriers is equal to the depth of the tuck of the paper tube, and they are in substantial parallelism with one another. The carriers 74 and 75 are also provided with hubs V and W, in which are pivoted side 10 clips 86 and 87 in substantially such position that the line passing through the intersecting points of the bevel-edged side clips and the edges of the tube form eventually the lower edges S of the completed bag-bottom. The 15 side clips 86 and 87 are adapted to vibrate toward and away from each other by mechanisms which will now be described.

Mounted upon the shaft 25 is a cam 88, having a groove 89, which is engaged by the 20 roller projection 90 of the arm 91, fastened on the rock-shaft 92 and having a bearing in the upwardly-extending bracket 20^a. On the outer free end of the shaft 92 the same is provided with an arm 93, having pivotally jointed 25 a connecting-rod 94, passing through an opening 21^a and engaging the lever 95, pivoted on the stud 96 on a projecting hub 21^a of the outside of the frame 21. On the upper end of the arm 95 is jointed the connector 30 97, passing through a central opening of the shaft 77 and being provided at its inner end with the flanged head 98, between the flanges of which a projection 99 is adapted to engage and forming a part of the lever 100, having 35 a segmental pinion at its lower end which engages the pinion 101 on the stud 102, to which the side clip 87 is securely fastened. The lower projecting arm of the side clip 87 carries, pivotally jointed, the connecting-rod 40 103, which engages a stud on the side clip 86. Any motion that is imparted by the cam-groove 89 of the cam 88 to the roller projection 90 controls the motion of the side clips 86 and 87.

50 Between the two carriers 74 and 75 is pivoted the lifting-plate 105 on the pivot 106, which has its bearings on the inner side of the carriers 74 and 75, and it is held by a spring-tension by the spring 107, coiled around the pivot 106, which has the tendency to lift the plate against the folding edge 50^a of the retainer during the oscillation of those carriers from the position as indicated in Fig. 8 through the stages of the formation of the 55 bag-bottom, as shown in Figs. 9, 10, and 11. The lifting-plate 105 is held in a downward position, as shown in Fig. 7, in order that the bottom-forming end of the bag-blank may more readily enter the bottom-forming mechanism by the engagement of the lifting-plate 105 with the stationary studs 108, depending from the retainer 50, as shown in Figs. 5, 6,

7 and 8. As the carriers are caused to oscillate away from the position as shown in Fig. 7 the lifting-plate 105, which is also supported by the carriers, is released from engaging the stationary stud 108, thereby permitting the spring 107 to carry the plate upward against the folding edge 50^a of the retainer and clamping the projecting end of the bag-blank between them. 75

The means for applying the paste to the bottom on the transverse paste-line and for communicating a rotary motion to the pasting device are as follows: Fastened on the shaft 80 33 on the outside of the frame 22 and adjacent to the cam 139 is the sprocket-wheel 120, engaging the chain 121, which effectively controls the rotation of a similar sprocket 122 on the paste-sector shaft 123, journaled in the 85 frame 22 and which carries on its inner side the paste-sector 124. The shaft 123 has also securely fastened thereon the gear 125, meshing into the paster-roll gear 126, securely fastened on the shaft 127, journaled in the paste-box 90 128 and which also carries the paster-roll 129. The paste-blade 130, mounted on the arm 131 and held on the shaft 132, receives its vibratory motion from the mechanism, as follows: On the shaft 132 is mounted on the outside 95 of the frame 22 a segment 133, engaging a segment 134, which is pivoted on a stud 135 and has a rearwardly-projecting arm 136, having a roller projection 137, engaging the cam-groove 138 of the cam 139, and whereby an 100 oscillatory motion is imparted to the paste-blade 130. The paste as it is delivered from the paste in the box 128 on the roll 129 is transferred upon the segment 134 and when the same is opposite the paste-blade 130 in its 105 upper position is delivered upon the edge of that paste-blade and from there onto the bag-blank when the blank is in about the position shown in Figs. 10 and 11; and upon the continuance of its oscillatory motion delivers the 110 completed bag-blank into the delivery-rolls 140 and 141, journaled on shafts 142 and 143, respectively, and receiving a rotary motion by the pulleys 144 145 and belt 146, held upon the shafts 140 and 25, respectively. 115

The operation of the machine is as follows: The paper of proper width to make the desired bag is taken from a roll and folded by any well-known mechanism (not shown in this application) into a tucked tube and drawn 120 into the rolls 39 and 40 under the serrated knife 45 and between the rolls 37 and 38 in such a manner that the float 46 is inside of the tube, and as the striker-arm 44 revolves across the path of the tube it forces the same 125 against the serrated edge of the knife 45 and the float 46 and severs the blank therefrom at each revolution. The rolls 37, 38, 39, and 40 are so geared in relation to the revolution of the striker as to feed through a suitable length at each rotation thereof. The bottom-forming end of the tube is then guided into the bottom-forming mechanism in such a manner that the same enters below the vibratory tucker-plate 130.

and the retainer 50, with its bevel-edged side nippers 51 and 52, and above the carriers 74 and 75, provided with the lifting-plate 105 and with the bevel-edged side clips 86 and 87. 5 The tube, as it arrives at about the position of Fig. 1, having a certain portion of the tube projecting beyond the folding edge 50^a, which eventually forms the transverse fold across the completed bag, is then held in its proper position by the side nippers entering between the tucks and holding the upper ply of the blank to the lower side of the retainer and simultaneously the side clips also entering those tucks to clasp the lower ply of the tube to the oscillating carrier and hold the tube for the subsequent folding. The tucker-plate 64 and the carriers 74 and 75 are then caused to be simultaneously vibrated by their respective cams. The lifting-plate being thereby released from the stud 108 engages the edge 50^a of the retainer by means of the spring 107, thereby transforming the bag through the stages, as shown at Figs. 8, 9, 10, and 11, unfolding the tube during the first half of the vibratory movement of the carriers and refolding the same into a bag during the last half of the movement of those carriers, and the edge of the tucker-plate forming the transverse crease and the folding 25 edges of the bevel-edged side clips and side nippers forming the characteristic inside triangular folds. The paste which is in the meantime being applied by the paste-blade 130 from the paste-sector 124 and the paste-roll 129 under the lip at the edge of the retainer and by the continued oscillatory motion of the blade 130 delivers the completed bag into the bite of the delivery-rolls 140 and 141, and from thence may be carried into a 30 drier to be dried and subsequently bound into packages ready for shipping and for commercial use.

It will be observed that after the side nippers 51 and 52, as well as the side clips 86 and 87, have been withdrawn from their respective coöperating mechanisms, such as the retainer-plate 50 and the carriers 74 and 75, the completed bag is resting only on the tucked-under tucker-blade 64 and can be 45 readily pushed into the bite of the delivery-rolls 140 and 141.

Having thus fully described this invention, what is claimed as new is as follows:

1. In a paper-bag machine, the combination of a stationary retainer; means adapted to hold the upper ply of the paper-bag blank to the lower surface of that retainer; the vibratory tucker-plate adapted to fold the transverse crease across the bag-blank; the carriers provided with means for holding the lower ply of the tucked-paper blank to the carriers; and the lifting-plate, all combined and operating to unfold the tucked-paper tube during the first half of the stroke of the carriers and refold it into a paper-bag blank during the last half of the stroke of the same.
2. In a paper-bag machine, the combination

of a stationarily-mounted retainer; bevel-edged side nippers adapted to move toward and away from each other; the vibratory tucker-plate mounted in the frames, the carriers provided with the lifting-plate and adapted to travel through the arc of a circle of about one hundred and eighty degrees; side clips mounted to those carriers and provided with means for an oscillatory motion toward and away from each other and hold the lower ply of the tucked-paper tube to the carriers, all combined and operating to unfold a paper tube during the first half of the stroke of the carriers and refold it into a paper-bag blank during the last half of the stroke of the same.

3. In a paper-bag machine, the combination of a stationarily-mounted retainer; bevel-edged side nippers adapted to move toward and away from each other; the vibratory tucker-plate mounted in the frames and provided with the folding edge, the distance from the center of vibration to that folding edge being substantially equal to the depth of the tuck; the carriers adapted to travel through the arc of a circle of about one hundred and eighty degrees; the lifting-plate mounted in the carriers, side clips mounted to those carriers and provided with means for an oscillatory motion toward and away from each other to respectively hold the lower ply of the tucked-paper tube to the carriers, and to release the same therefrom, all combined and operating to unfold a paper tube during the first half of the stroke of the carriers and refold it into a paper-bag blank during the last half of the stroke of the same.

4. In a paper-bag machine, the combination of a stationarily-mounted retainer; bevel-edged side nippers adapted to move toward and away from each other at predetermined intervals, and operated by a cam; the vibratory tucker-plate mounted in the frames and provided with the folding edge, the distance from the center of vibration to that folding edge being substantially equal to the depth of the tuck; the carriers adapted to travel through the arc of a circle of about one hundred and eighty degrees; the lifting-plate mounted in the carriers, side clips mounted to those carriers and provided with means for an oscillatory motion toward and away from each other to respectively hold the lower ply of the tucked-paper tube to the carriers, and to release the same therefrom, all mounted and operating to unfold a paper tube during the first half of the stroke of the carriers and refold it into a paper-bag blank during the last half of the stroke of the same.

5. In a paper-bag machine, the combination of a stationarily-mounted retainer; bevel-edged side nippers adapted to move toward and away from each other at predetermined intervals and operated by a cam; the vibratory tucker-plate mounted in the frames and provided with the folding edge, the distance from the center of vibration to that folding

edge being substantially equal to the depth of the tuck; the carriers adapted to travel through the arc of a circle of about one hundred and eighty degrees; the lifting-plate 5 mounted in the carriers, side clips mounted to those carriers and provided with means for an oscillatory motion toward and away from each other to respectively hold the lower ply of the tucked-paper tube to the carriers and 10 to release the same therefrom at predetermined intervals and operated by a cam; all mounted and operating to unfold a paper tube during the first half of the stroke of the carriers and refold it into a paper-bag blank 15 during the last half of the stroke of the same, substantially as described.

6. In a paper-bag machine, the combination of a stationarily-mounted retainer; bevel-edged side nippers adapted to move toward 20 and away from each other at predetermined intervals and operated by a cam; the vibratory tucker-plate mounted in the frames and provided with the folding edge, the distance from the center of vibration to that folding 25 edge being substantially equal to the depth of the tuck; means for operating that tucker-plate by a cam; the carriers adapted to travel through the arc of a circle of about one hundred and eighty degrees; the lifting-plate 30 mounted in the carriers, side clips mounted to those carriers and provided with means for an oscillatory motion toward and away from each other to respectively hold the lower 35 ply of the tucked-paper tube to the carriers and to release the same therefrom at predetermined intervals and operated by a cam; all mounted and operating to unfold a paper tube during the first half of the stroke of the carriers and refold it into a paper-bag blank 40 during the last half of the stroke of the same, substantially as described.

7. In a paper-bag machine, the combination of a stationarily-mounted retainer; bevel-edged side nippers adapted to move toward 45 and away from each other at predetermined intervals and operated by a cam; the vibratory tucker-plate mounted in the frames and provided with the folding edge, the distance from the center of vibration to that folding 50 edge being substantially equal to the depth of the tuck; means for operating that tucker-plate by a cam; the carriers adapted to travel through the arc of a circle of about one hundred and eighty degrees, and means for operating 55 those carriers by a cam; the lifting-plate mounted in the carriers, side clips mounted to those carriers and provided with means for an oscillatory motion toward and away 60 from each other to respectively hold the lower ply of the tucked-paper tube to the carriers and to release the same therefrom at predetermined 65 intervals and operated by a cam; all mounted and operating to unfold a paper tube during the first half of the stroke of the carriers and refold it into a paper-bag blank during the last half of the stroke of the same, substantially as described.

8. In a paper-bag machine, the combination of a stationary retainer; means adapted to hold the upper ply of a paper-bag blank to 70 the lower surface of that retainer; a vibratory tucker-plate mounted in the stationary frame in substantially such a position that the center of vibration of the tucker-plate coincides with the predetermined corners of the 75 bag-blank, and having a folding edge adapted to form a transverse fold across the blank; the carriers, the lifting-plate, means adapted to hold the lower ply of the tucked-paper tube to the top surface of the carriers, the carriers 80 being mounted in substantially such a position that the distance from the center of oscillation of the carriers to the center of oscillation of the vibratory tucker-plate is substantially the depth of the tuck, substantially 85 as described.

9. The combination of a stationary retainer having a folding edge; means for holding the upper ply of the tube to the lower surface of that retainer; a vibratory tucker-plate having 90 a folding edge, the distance from the center of vibration of the tucker-plate to its folding edge being substantially equal to the distance from the center of vibration of the tucker-plate to the folding edge of the retainer, substantially as described and set forth.

10. The combination of a stationarily-mounted retainer having a folding edge; means for holding the upper ply of the tube to the lower 100 surface of the retainer; a vibratory tucker-plate having a folding edge, the distance from the center of vibration of the tucker-plate to its folding edge being substantially equal to the distance from the center of vibration of 105 the tucker-plate to the folding edge of the retainer, substantially as described; the carriers, the lifting-plate, means adapted to hold the lower ply of the tucked-paper tube to the carriers, all combined and operating to unfold 110 the tucked-paper tube during the first half of the stroke of the carriers and refold it into a paper-bag blank during the last half of that stroke, substantially as described.

11. In a paper-bag machine, the combination of a stationary retainer having a folding edge; means for holding the upper ply of the tube to the lower surface of the retainer; a vibratory tucker-plate having a folding edge, the distance from the center of vibration of 120 the tucker-plate to its folding edge being substantially equal to the distance from the center of vibration of the tucker-plate to the folding edge of the retainer; carriers mounted in substantially such position that the center of oscillation of those carriers coincides with the folding edge of the retainer; the lifting-plate mounted in the carriers, means to hold the lower ply of the tube to the carriers, all combined and operating to unfold the tucked-paper tube during the first half of the stroke of 125 the carriers and refold it into a paper-bag blank during the last half of that stroke, substantially as described.

12. In a paper-bag machine, the combination of a stationary retainer having a folding edge; means for holding the upper ply of the tube to the lower surface of the retainer; a vibratory tucker-plate having a folding edge, the distance from the center of vibration of the tucker-plate to its folding edge being substantially equal to the distance from the center of vibration of the tucker-plate to the folding edge of the retainer; the two oppositely-disposed carriers mounted in stationary frames on each side of the tucked-paper tube, in substantially such position that the center

of oscillation of those carriers coincides with the folding edge of the retainers; the lifting-plate mounted in the carriers, means to hold the lower ply of the tube to the carriers, all combined and operating to unfold the tucked-paper tube during the first half of the stroke of the carriers and refold it into a paper-bag blank during the last half of the stroke, substantially as described. 15
